BOBBIN DRAG MEANS FOR SPINNING FRAMES AND SIMILAR MACHINES

Eduard Vokurka, Porici, near Trutnov,
CzechoslovakiaApplication July 6, 1950, Serial No. 172,248
In Czechoslovakia February 14, 1950

3 Claims. (Cl. 57—70)

1

The present invention relates to improvements in a spinning cap for cap spinning frames and similar machines.

It is a well known fact that the velocity of the spinning operation depends on the strength of the material to be spun and on the stress placed thereon during the spinning operation. The stress is produced in particular by the centrifugal force and by the resistance of air and manifests itself by the formation of a balloon, in particular in connection with ring spinning machines. If the operation is carried out in wet condition the above deficiencies are still further increased by the weight of water contained in the yarn. An increase in the speed of operation causes the stress in the balloon to be raised in square and this fact is prohibitive to a substantial increase of speed and efficiency of such machines.

It has already been proposed to eliminate the said drawbacks by means of a spinning cap having for its purpose to entrain the yarn balloon by its rotation without contacting the same; this provision has partially removed the stress caused by the resistance of air. To this end the known spinning cap is provided at its open end with an inwardly directed flange, the inner circumference of which carries a guiding eyelet so that there is nothing to hinder the thread or yarn supplied through the hollow axis of the spinning cap from forming a balloon.

The main object of the present invention is to provide a spinning cap which removes the above drawbacks and completely eliminates the stress placed on the yarn by the formation of the balloon and resistance of air.

A further object of the invention is to provide a spinning cap of a very simple design by means of which the efficiency of ring spinning and similar machines may be considerably increased.

Another object of the invention is to provide a spinning cap which considerably simplifies the design of the machine with which it is employed.

Further objects and advantages of the invention will appear from the ensuing description.

According to the invention the spinning cap for ring spinning or similar machines is provided with a hollow axial cavity for the supply of yarn and the guiding eyelet for the yarn is provided immediately adjacent the lower edge of the cap.

The yarn or thread passing through the axial cavity adheres very soon after entering the interior of the cap to the inner wall thereof and is dragged along the same and thus smoothed on its circumference. The pull produced by the

yarn or thread dragged in this way along the wall of the spinning cap at high revolutions is made use of for imparting rotation to the spindle carrying the bobbin; the drive of the spindle which is otherwise indispensable may then be dispensed with and the whole spinning operation is performed by the drive of the spinning cap only. In order to control the speed of rotation of the bobbin braking means are provided on the spindle preferably in the point where the whirl is normally mounted, said braking device being of the centrifugal fan type provided with a blade ring. The upper cover of the fan against which the bobbin abuts is a full disc whereas the lower cover is provided with a suction orifice engaged from below by a conical plug which may be withdrawn from the orifice and in this way open or close the latter.

The invention will now be described on hand 20 of the accompanying drawing showing an example of the spinning cap according to the invention.

In the drawing;

Figure 1 shows a part elevational view and 25 partially a longitudinal section through the entire arrangement of the spinning cap;

Figure 2 shows on a larger scale a longitudinal section through the spinning cap itself and;

Figure 3 is a cross-sectional view taken along the line A—A from Figure 2 showing the mounting of the spindle.

In the frame 1 of the machine, a head portion 2 of a spinning cap 3 is mounted for rotation in frictionless bearings, said head portion being provided with an axial cavity for the passage of the yarn into the interior of the spinning cap 3. A driving pulley 4 is mounted on the head portion 2.

The spinning cap 3 may have substantially the 40 shape of a cylindrical body (which may be called the operative portion of the cap), with an adjoining spherical portion at its upper end extending into the said cylindrical head 2, as clearly shown in the drawing. Immediately adjacent the lower edge of the inner portion of the spinning cap 3 the guiding eyelet 5 is provided. The bobbin 6 is closely fitted on a spindle 7 mounted in a sleeve 8, which is carried by a holder 9. The end of the spindle 7 together with the sleeve 8 is secured 45 in the holder 9 by a grub screw 10 or by any similar means. The holder 9 is mounted for sliding movement in a carriage 11 of the machine and maintained by a spring 13 in a position in which 50 its abutment 12 rests against the lower surface

of the carriage 11. The spindle 7 is provided in its lower portion with a spiral groove for lubricating purposes and its lower conical end rests against a hard bearing plate 14. The spindle 7 is therefore freely rotatable in its seat in the sleeve 8. Details of the mounting are apparent from Figs. 2 and 3.

In the part of the spindle occupied normally by the whirl a fan 15 is provided, said fan comprising blades of any desired design and operating as an air brake. The fan has a full top cover 18 and its lower cover 19 consists of a ring the central orifice of which serves as the aspiration orifice of the fan. A conical plug 16 is mounted for reciprocal movement on the holder 9 on a thread; 15 preferably on a multiple thread. The conical end of the plug 16 is adapted to engage the aspiration orifice in the fan 15 and according to its longitudinal position to open or to close said orifice and so to change the efficiency of the braking fan 15.

The longitudinal movement of the plug 16 is controlled by a rack 17 engaging with corresponding teeth on the circumference of the plug 16.

The spinning cap, according to the invention operates as follows:

The yarn or thread is introduced through the axial cavity in the head portion 2 of the spinning cap and passed through the eyelet 5 at the lower end of the cap and fastened to the bobbin 6 on the spindle 7. Rotation is now imparted to the spinning cap by means of the pulley 4 from the main drive of the machine. In consequence of the quick rotation of the spinning cap 3 the yarn is now spun in the usual way but it will adhere to the inner walls of the cap, be dragged along the same and in this way smoothed on its circumference. This dragging movement produces a certain tension or pull which sets the bobbin 6 in rotation. The velocity of rotation of the bobbin may be controlled by the braking fan 15 by means of the plug 16. The plug, as already disclosed, may be moved longitudinally by means of the rack 17 so as to close or uncover the suction orifice of the fan 15 as desired. The more the plug 16 is withdrawn from the suction orifice, the larger amount of air is aspirated by the fan 15 and the greater the braking action on the spindle 7, and vice versa.

As disclosed above, the spinning cap according to the present invention removes entirely any stress placed on the yarn in consequence of the formation of the balloon and resistance of air. The spinning machine may therefore operate with higher velocities than heretofore possible, which fact considerably increases the efficiency of such machines.

While I have disclosed the principles of my invention in connection with one embodiment it will be understood that this embodiment is given by way of example only, and not as limiting the scope of the invention as set forth in the appended claims.

I claim:

1. In a spinning machine, in combination, a supporting shaft having a threaded portion; a spindle rotatably mounted with one end portion thereof in an axial bore of said supporting shaft; a bobbin closely fitted on the other end portion of said spindle; a braking air fan fixedly mounted

on said spindle and provided with a conical suction orifice extending coaxially with and around said spindle; a conical plug provided with an inner thread and mounted therewith on said threaded portion of said supporting shaft for longitudinal reciprocal movement, said conical plug being provided with an outer gear; and a rack bar mounted on the spinning machine for reciprocal movement and engaging said outer gear of said conical plug whereby said plug may be rotated on said threaded portion of said supporting shaft so as to move into and out of said suction orifice thereby controlling the same and the braking action of said fan.

2. In a spinning machine, in combination, a supporting shaft having a threaded portion consisting of a multiple thread; a spindle rotatably mounted with one end portion thereof in an axial bore of said supporting shaft; a bobbin closely fitted on the other end portion of said spindle; a braking air fan fixedly mounted on said spindle and provided with a conical suction orifice extending coaxially with and around said spindle; a conical plug provided with an inner multiple thread and mounted therewith on said threaded portion of said supporting shaft for longitudinal reciprocal movement, said conical plug being provided with an outer gear; and a rack bar mounted on the spinning machine for reciprocal movement and engaging said outer gear of said conical plug whereby said plug may be rotated on said threaded portion of said supporting shaft so as to move into and out of said suction orifice thereby controlling the same and the braking action of said fan.

3. In a spinning machine, in combination, a supporting shaft; a spindle rotatably mounted with one end portion thereof in an axial bore of said supporting shaft; a bobbin closely fitted on the other end portion of said spindle; a braking air fan fixedly mounted on said spindle and provided with a conical suction orifice extending coaxially with and around said spindle; a conical plug mounted on said supporting shaft for longitudinal reciprocal movement; and actuating means mounted on the spinning machine and adapted to move said plug into and out of said suction orifice thereby and controlling the same and the braking action of said fan.
